UNITED STATES PATENT OFFICE

157,429

AUTOMOBILE HOOD ORNAMENT

Harry A. Richman, Chicago, Ill.

Application March 15, 1949, Serial No. 1,410

Term of patent 7 years

(CL. D14—18)

To all whom it may concern:

Be it known that I, Harry A. Richman, a citizen of the United States, residing at Chicago, in the county of Cook and State of Illinois, have invented a new, original, and ornamental Design for an Automobile Hood Ornament, of which the following is a specification, reference being made to the accompanying drawing, forming a part thereof:

In the drawing:

Fig. 1 is a side elevational view of an automobile hood ornament embodying my new design;

Fig. 2 is a top plan view of the same;

Fig. 3 is a front end elevational view as seen from the left hand end in Figs. 1 and 2; and

Fig. 4 is a rear end elevational view as seen from the right hand end in Figs. 1 and 2.

I claim:

The ornamental design for an automobile hood ornament, substantially as shown.
